US0D1051592S

(12) **United States Design Patent** (10) **Patent No.:** **US D1,051,592 S**
(45) **Date of Patent:** **** Nov. 19, 2024**

(54) **SELF-DEFENSE SURVIVAL TOOL
KEYCHAIN**

(71) Applicant: **Franck Pala**, Miami, FL (US)

(72) Inventor: **Franck Pala**, Miami, FL (US)

(**) Term: **15 Years**

(21) Appl. No.: **29/869,712**

(22) Filed: **Jan. 6, 2023**

(30) **Foreign Application Priority Data**

Jul. 21, 2022 (EM) 009094006-0001

(51) **LOC (14) Cl.** **03-01**

(57) **CLAIM**

The ornamental design for a self-defense survival tool keychain, as shown and described.

DESCRIPTION

FIG. 1 shows a perspective view of a self-defense survival tool keychain;

FIG. 2 shows a left side view of the self-defense survival tool keychain;

FIG. 3 shows a right side view of the self-defense survival tool keychain;

FIG. 4 shows a front view of the self-defense survival tool keychain;

FIG. 5 shows a rear view of the self-defense survival tool keychain;

FIG. 6 shows a top plan view of the self-defense survival tool keychain;

FIG. 7 shows a bottom plan view of the self-defense survival tool keychain; and,

FIG. 8 shows an exploded view of the keychain with a survival self-defense tool, key ring, and cord.

The portion of FIG. 8 shown in dashed lines is for the purpose of illustrating environmental structures, a survival self-defense tool, key ring, and cord, and form no part of the claimed design.

1 Claim, 3 Drawing Sheets
